SOLE AND HEEL FOR FOOTWEAR

Michael R. Haider, Los Angeles, Calif.

Application December 13, 1933, Serial No. 702,218
Renewed June 24, 1935

2 Claims. (Cl. 36—59)

My invention relates to a removable and replaceable wearing attachment for foot-wear, in which the main portion of the wearing attachment of the sole and heel may be readily replaced.

An object of my invention is the construction of the wearing portion of foot-wear with a series of replaceable rubber or resilient studs which are held in place on the sole by a flexible plate. If the studs become worn, the holding plate may be removed and new studs substituted, the plate again clamping the studs to the sole and the heel.

A further feature of my invention in relation to the heel is forming this with a plurality of sockets or recesses in which are located the studs. The studs each have a shoulder which is engaged by the clamping or locking plate, the latter being attached to the heel by a screw bolt, the plate having a perforation for each stud.

The wearing studs for the main portion of the sole are preferably attached to strips of rubber, the strips being of sufficient length to reach from side to side of the shoe, and they may be trimmed to the shape of the sole. This rubber strip is engaged by a perforated plate, a stud extending through each perforation, whereby such flexible plate with the studs may be attached to the sole.

My invention is illustrated in connection with the accompanying drawing in which:—

Fig. 1 is the under-side view of a shoe showing the sole and heel construction.

Fig. 2 is a transverse section on line 2—2 of Fig. 1 through the sole construction.

Fig. 3 is a transverse section on the line 3—3 of Fig. 1 in the direction of the arrows through the heel construction.

Fig. 4 is a perspective view of one of the strips having studs for use on the sole.

Fig. 5 is a perspective view of one of the insertable studs used for the heel.

Referring to the drawing, a heel construction is indicated by the numeral 11, in which there are a series of sockets or recesses 12 preferably around the edge of the heel, and in each of these sockets, there is a stud 13. These studs are preferably formed with a large cylindrical section 14, an annular shoulder 15, and a reduced cylindrical section 16. They are preferably formed with a hollow chamber or space 17 to form a better cushion. The end 18 of each stud is preferably flat. The studs are inserted in the sockets so that the shoulders are substantially flush with the lower surface 19 of the heel.

A holding and clamping plate 20 of strong flexible material and which has perforations for the studs is then fitted over the studs engaging the shoulders 15. The plate with the studs is then clamped in place by means of a screw 21 extending through the plate and having a head with a kerf 22 for engaging by a screw driver. The screw preferably threads into a nut 23 embedded in the heel, and thus firmly attaches the clamping plate and the studs to the heel.

In the construction of Figs. 1 and 2, a shoe sole is indicated by the numeral 24, and against the lower face of this, there is fitted resilient strips 25 each having a plurality of studs 26. The studs are indicated as cylindrical and each has a hollow chamber 27 forming a cushion, if desired. The strips are generally formed rectangular and are fitted close together with their adjacent edges adjoining as indicated at 28. A flexible tough clamping plate 29 has a series of perforations 30 to engage each stud or knob. The plate is then secured to the sole by means of a series of screws 31, these screws each having a head 32, with a screw driver kerf 33. The strips may be assembled on the sole by means of the clamping plate and then trimmed the shape of the sole or they may be cut to shape before being clamped to the sole. It is desirable to have a toe strip indicated at 34 with a few larger studs 35 to take the increased wear at the toe portion of the sole.

When it is desired to remove the studs from the heel, the clamping plate for the heel is removed and the worn studs are also removed from their recesses, and new studs used to replace them. The clamping plate is then secured in position. In the construction of the sole, if the studs become worn, the clamping plate may be removed and one or more strips 25 with studs may be used for replacement.

Various changes may be made in the details of construction without departing from the spirit or scope of the invention as defined by the appended claims.

I claim:—

1. In a shoe having a bottom wearing portion provided with a cylindrically shaped socket, a stud having a cylindrical portion fitting in the socket and having an annular shoulder in alignment with the lower surface of the bottom wearing portion with a projection portion above the shoulder, a plate having a perforation for the projecting portion of the stud, the plate engaging the shoulder, and screws attaching the plate to the bottom wearing portion, the stud having

a cavity completely enclosed in the stud and located substantially in alignment with the plate.

2. In a shoe a heel construction having peripheral side walls and a plane bottom surface, the heel having a series of cylindrical sockets extending upwardly from the bottom surface and positioned slightly spaced from the periphery of the heel, each of the sockets having a flat base forming the upper end of the socket, each base being parallel to the bottom surface, a resilient stud fitted in each socket, each stud having a cylindrical upper part of relatively large diameter fitting in the cylindrical socket and having an upper end engaging the base of the socket, each stud having a lower cylindrical

portion of reduced diameter and an annular shoulder at the connection between the upper and lower portions of the stud, each shoulder being substantially in alignment with the plane of the said bottom surface, a metal plate having a series of perforations, one for each stud, the lower portion of each stud extending through a perforation, and said plate being in contact with the said bottom surface and the shoulder of each stud, and means to secure the plate to the heel 10 construction, each stud having a completely enclosed hollow space located at substantially the line of the shoulder of the stud. 5
